Attorney.

UNITED STATES PATENT OFFICE.

BERTON M. MATHIAS, OF MINNEAPOLIS, MINNESOTA.

GUY-STRAND CLAMP.

1,275,283.

Specification of Letters Patent. Patented Aug. 13, 1918.

Application filed December 1, 1916. Serial No. 134,496.

To all whom it may concern:

Be it known that I, BERTON M. MATHIAS, a citizen of the United States, and a resident of Minneapolis, in the county of Hennepin 5 and State of Minnesota, have invented certain new and useful Improvements in Guy-Strand Clamps, of which the following is a specification.

One object of my invention is to provide 10 in a guy strand clamp, means for preventing the loop and the guy strand from spreading at the clamp itself.

Another object of my invention is to provide in a strand clamp, means for creating a 15 stronger grip on the dead end of the strand than on the live end.

Another object of my invention is to provide means for maintaining the stress on the 20 bolts in an axial direction and thus preventing the bolts from bending.

With these and incidental objects in view, the invention consists of certain novel features of construction and combinations of parts, the essential elements of which are 25 hereinafter described with reference to the drawing which accompanies and forms a part of this specification.

In the drawing, Figure 1 is a side elevation of my preferred construction as applied 30 to a looped strand. Fig. 2 is a section taken on the line A A Fig. 1, and Fig. 3 shows a modified section on the same line A A as an alternate construction.

Fig. 4 discloses an alternate construction 35 of the retainer, and Fig. 5 still further alternate construction.

Fig. 6 is a modified form of clamp using 40 straight bolts instead of U bolts; Fig. 7 is a section taken on the line B B Fig. 6; and Fig. 8 is a section taken on the line C C Fig. 6.

Fig. 9 is an end view of the clamp shown 45 in Fig. 1 as viewed from the direction of the arrow D; Fig. 10 is a section taken on the line E E Fig. 9; and Fig. 11 is an enlarged detail of a preferred form of washer.

The prime object of my invention is to 50 combine with a clamp a retainer. In my preferred construction, I employ a body member 1, having formed at one end thereof, a loop or retainer 2 having the opening 3, Fig. 2, sufficient to easily pass therethrough the ends of the guy strand 4.

The end 5 of the guy strand takes the 55 strain for which the strand is used, and the large loop 6 is passed around a pole or stub

which tends to spread the strand apart at 7 were it not for retainer 2.

The dead end of the strand 8 is passed 60 through the clamp proper at 9, and this clamp may comprise a U bolt or clamping members of any other suitable style of uniting clamp members on the guy strand.

As shown in Fig. 1, the inner grooved surface of the body 1 is corrugated at 10 as the 65 dead end of the strand has more tendency to slip from the clamp than the strain end of the strand.

Instead of having the retainer 2 formed in a letter O style, I may form it in a C shape 70 as shown in Fig. 3 so as to allow the strands to be slipped through the opening of the C instead of threaded through as necessary with the O shaped retainer; or I may have the retainer in the form of a separate part 75 11, Fig. 4, butting on the end 12 of the body member 2, the end 12 being preferably formed at an angle as shown to better position the retainer for the strains set up by the loop. 80

In Fig. 5, I show a construction wherein the retainer 2 is replaced by a U shaped member 13, fastened to the body 2 by a bolt or pin 14.

For some classes of work, the body member is better formed as at 15, Fig. 6, terminating in one end in the retainer 2 and co-acting with a plate 16 by means of bolts 17. 85

Where the guy strands are small and it is difficult to work the nuts on the U bolt used 90 in Fig. 1, I find it advantageous to form this U bolt with a substantially oval cross-section as shown in Fig. 10, thereby spacing the center lines of the bolt farther apart without modifying the fitting of the U bolt with 95 the small guy strand.

With any of the constructions shown, I may use as an addition to the nuts on the bolts, a rocking washer 18 and form the body 2 with a depression 19 registering with the 100 rocking washer so as to insure the strain always coming evenly on the bolt. With this construction, even though the U bolt or straight bolt, whichever the case may be, is drawn out of line by the guy strand, the 105 strain in the bolt itself will be in an axial direction, and hence the bolt will not bend under the strain.

While I have described my invention and 110 illustrated it in several designs, I do not wish it understood that I limit myself to these constructions, as the application in

my invention may be varied in many ways within the scope of the following claims:

Claims—

1. In a guy strand clamp, the combination of clamping means, a retainer spaced from said clamping means, to prevent spreading of the guy strand passing therethrough, a bolt, nut and washer forming a part of said clamping means, said washer having a curved projection thereon to register with a co-acting depression in said clamping means for the purpose of maintaining tension set up in said bolt in an axial direction.
2. In a guy strand the combination of a body member, a **U** bolt co-acting therewith to form therewith clamping means, said **U** bolt having an ovoid cross-section at its **U** shaped end, and retaining means associated with said body, spaced from said **U** bolt to prevent spreading of strands passing therethrough.
3. In a guy strand clamp the combination of a non-clamping body member, clamping means carried at one end of said body member, and a non-clamping retainer of a **C** shape carried at the other end of said body member to retain therein two guy strands, thereby preventing the spreading of said strands at said clamping means.

BERT M. MATHIAS.
